UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

FEED MECHANISM.

1,253,322.

Specification of Letters Patent. Patented Jan. 15, 1918.

Application filed May 28, 1915. Serial No. 31,019.

To all whom it may concern.

Be it known that I, RICHARD LESTER WILCOX, a citizen of the United States, residing at Waterbury, in the county of New Haven and State of Connecticut, have invented certain new and useful Improvements in Feed Mechanism, of which the following is a specification, reference being had therein to the accompanying drawings.

My invention relates to a new and improved feed mechanism and is especially adapted for use upon a header although not limited thereto, being capable of attachment to any form of mechanism requiring a reliable feed.

It is the object of my invention, among other things, to produce a feed mechanism, preferably of the friction type, controlled by a mechanism that is readily accessible, easily manipulated, and which will stop the feed when desired, as well as controlling the movements thereof so that it will be impossible to operate the same except at the proper time and then always assuring a full length feed.

To these and other ends, my invention consists in the feed mechanism, having certain details of construction and combinations of parts, as will be hereinafter described and more particularly pointed out in the claims.

Referring to the drawings, in which like numerals of reference designate like parts in the several figures:

Fig. 1 is a side elevation of a header having my improved feed mechanism connected therewith;

Fig. 2 is a fragmentary plan view of one end of the header and the feed mechanism;

Fig. 3 is an enlarged sectional view of the parts taken upon line C—D of Fig. 2;

Fig. 4 is an enlarged sectional view of the parts taken upon line G—H of Fig. 3;

Fig. 5 is an enlarged sectional view of the parts taken upon line E—F of Fig. 3;

Fig. 6 is a detail view of the link block adjusting mechanism;

Fig. 7 is a sectional view of the shifter arm taken upon line A—B of Fig. 1;

Fig. 8 is a plan view of the latch mechanism; and Fig. 9 is a view of the means for connecting the feed link and shifter arm.

The feed mechanism as shown and described herein is constructed without a pawl and ratchet, friction devices being substituted therefor, and elements movable in the path of said friction devices are provided to release their grip and stop the feed. This latter feature is controlled from a handle that is mounted upon a fixed part, its position thereby being always substantially the same and materially enhancing the convenience of its operation as distinguished from the type of pawl mechanisms above referred to, wherein the pawl usually moves about the axis of the pawl disk and must be grasped while in motion. In the latter form it is apparent that the more rapid the feed, the more difficult it is to grasp and operate the continually moving pawl.

The length of the stroke of the feed mechanism is adjustable, means being provided for accomplishing this through a coarse adjustment and a fine adjustment, either one or both of which may be dispensed with if desired.

In the drawings the numeral 1 designates the body of the machine supported upon legs 2 and within which is rotatably mounted the crank shaft 3 having a fly wheel 4 and a pinion 5 thereon, which latter meshes into 6 and imparts motion to a gear 6 fixed upon a shaft 7 rotatably mounted in the underside of said body. All of the parts just described are common and well known in the art and require no additional description or illustration herein.

Journaled in the body 1 is a shaft 8, to which a rocking movement is imparted through the shifter arm 9, either integral therewith or fixed thereon, as may seem most desirable, through a shifter connection 10, having rolls 11 and 12 thereon in contact with the periphery of the cam 13. An adjustable connection between said shifter connection and shifter arm is provided, comprising a stud 14, having a block 15 thereon, that slides within the opening 16 in the shifter connection 10, and a washer 17, held in place by a nut 18 to prevent movement of said block within the opening 16. Said stud 14 passes through an opening 19 in the shifter arm 9 and is adjustable through a screw 20.

held against endwise movement by a pin 21, a washer 22 and a nut 23 locking said stud 14 to the shifter arm 9 when in its adjusted positions. The relative position of the block 15 within the shifter connection 10 is determined by the position of the stud 14 within the opening 19 of the shifter arm 9, and the same is locked in any of its positions by the screws 24 and 25 which impinge against the 10 opposite ends of the said block. It is obvious that the closer the stud 14 is moved toward the center of the shaft 8, the greater will be the arc through which the rock shaft 8 will travel, and vice versa, thereby providing 15 means for varying the length of stroke of the feed mechanism. It will be observed that all of the mechanisms necessary to accomplish this adjustment are upon the outside of the machine, are readily accessible, 20 and easily controlled.

The dies are designated by the numeral 27 and have a lateral movement within the body 1 through the reciprocating action of the plate 28 by means not herein shown or 25 described, and travel so that the grooves in the meeting faces thereof pass from the line of the wire feed, designated 29, to the line of the heading operation, designated by the numeral 30. The dies are held against the 30 plate 28 and returned to the line 29 by mechanism comprising the plate 31 connected to the ends of the slidably mounted rods 32, having a head bracket 33 thereon, against which the end of a spring 34 is secured at its 35 opposite end to the body 1 by a cap 35. A screw 36 threaded through the head bracket 33 and abutting against the bed 1, limits the inward movement of the parts just described.

40 Pivottally secured on the stud 37 is the trip latch 38 having trip arms 39 and 40 thereon, through the latter of which is an adjusting screw 41 that lies within the path of movement of the head bracket 33. This 45 latch is subject to the pressure of a spring 42 that bears against the end of a pin 43 contacting with the arm 39 and actuates the said latch to move the trip arm 39 away from the body 1.

50 Connected with the body 1 is a roll frame 44, within which are rotatably mounted the shafts 45 and 46, each of which is provided with a feed roll 47 and intermeshing gears 48 and 49. In one face of the gear 49 is a 55 ring 50 and concentric therewith is a clutch plate 51 secured by screws 52, and having a plurality of notches 53 in the edge thereof, said notches having roll faces 54 and an end face 55. Within each of said notches is 60 a roll 56 that is moved in one direction between the face 54 and the inner face of the ring 50 by a pin 57 having a head 58 thereon with an angular face which contacts with the roll 56. A spring 59 pressing against

the end of the pin 57 provides a yielding 65 pressure against the roll 56.

Rotatably mounted upon the roll shaft 46 is a trip head 60 having the offset arm 61 integral therewith, within which is mounted the block 62 that is adjustable through a 70 screw 63 threaded therein and rotatable within the trip head 60 with a spiral gear 64 thereon which meshes into a spiral gear 65 fixed upon a shaft 66 rotatable in the trip head 60 through a knob 67 fixed upon the 75 outer end thereof. The position of the knob 67 is so relatively close to the center of the shaft 46 that its circular movement is very limited and it may be readily rotated during the movement of the trip head 60 to vary 80 the radial position of the block 62 within the arm 61. A link 68 that connects the shifter arm 9 and block 62 is secured to the latter by a pin 69 and to the former by a pin 70, which is held against accidental disengagement by a catch plate 71 rotatably secured to the link by a screw 72 and which enters an annular groove 73 in the pin 70. This catch plate and its method of operation constitute no part of my present invention. 85 The length of stroke of the link 68 is varied by shifting the point of connection thereof with the shifter arm 9, this being accomplished by passing the pin 70 through any one of a plurality of holes 74 in the said shifter arm. This adjustment is generally known as a coarse adjustment. The fine adjustment of the feed is determined by the radial position of the block 62 within the offset arm 61, which, as above described, is secured by rotation of the knob 67. 90 100

As the shifter arm 9 moves to the left, as shown in Fig. 1, the trip head 60 is moved in the direction shown by the arrow in Fig. 3, at which time the clutch plate 51 (which is fastened to the trip head 60) moves the rolls 56 against the faces 54, assisted by the action of the pins 57 and springs 59 so that the rolls impinge against the inner surface of the ring 50, causing a frictional engagement between all of the parts. The ring 50 will now rotate, and through it, the gear 49, with which it is connected, which rotation in turn is transmitted to the gear 48, shafts 46 and 45 to the rolls 47, causing the same to 110 115 impart an endwise feed movement to the wire therebetween.

Upon the reverse movement of the shifter arm 9, the trip head 60 is moved in the opposite direction, and the clutch plate 51, having faces 54, contacts with the periphery of each of the rolls 56 and moves them against the heads 58, and the tension of the spring 59. The effect of this action is to break the connection therewith so that the trip arm rotates freely without imparting movement to the feed mechanism. 120 125

Immediately upon the movement of the

shifter arm 9 being reversed from that last described, the friction hold of the rolls 56 between the clutch 51 and the ring 50 takes place, and all of the parts move with the motion of the trip head 60.

The mechanism for stopping the feed operation comprises a disk 75, which is rotatably mounted upon the trip head 60, with one face thereof against the face of the ring 50 (see Fig. 4), and inclosed within an overhanging lip 76 upon the gear 49. Fixed within this ring are a plurality of release pins 77, corresponding in number with the rolls 56, and projecting into the path of movement thereof and lying between the roll face 54 and the ring 50. The centers of these release pins 77 are more distant from the center of the shaft 46 than that of the rolls 56, so that as they engage the said rolls they have a tendency to force the same against the face 54 and away from the inside of the ring 50.

Rotatably mounted upon a stud 78 fixed in the trip head 60, is a release arm 79 that is connected with the disk 75 through the pin 80, and having a roll 81 rotatably mounted upon one end thereof. A spring 82 connected at one end to a pin 83 in the outer end of the offset arm 61, and at the other end to the pin 80, always exerts its tension so as to rock the release arm 79 upon its pivot mounting and move the disk 75 upon its axis so as to force the release pins 77 into contact with the rolls 56.

Pivoted secured to the body 1 upon the stud 84, is a roll arm 85, which is connected with the handle 86 by the link 87. The handle 86 is provided with a tail-piece 88, and is rotatably mounted upon a fixed stud 89. In Figs. 1 and 3, the roll arm 85 is shown in such position that the curved portion or sweep thereof is concentric with the axis of the shaft 46, in which position the roll 81 rides against its inner face, being held thereby by the spring 82. While the parts are in these relative positions the disk 75 moves with the trip head 60 as a unit, and the release pins 77 and rolls 56 occupy the relative positions substantially as shown in Fig. 3.

To move the rolls 56 so as to prevent them having a frictional engagement with the clutch 51 and ring 50, the handle 86 is moved upon its pivot mounting to the position shown by broken lines in Figs. 1 and 3, which brings the roll arm 85 to the position shown by broken lines in Figs. 1 and 3, wherein the curved portion or sweep thereof is eccentric to the axis of the shaft 46.

The spring 82 still maintains the roll 81 in contact therewith, but while moving to this latter position, the release arm 79 is moved upon its pivot mounting and an independent movement is given to the disk

75 through the pin 80, and the release pins 77 are moved against the rolls 56, which shift and break their frictional engagement between the clutch face 54 and the ring 50. So long as the roll arm 85 occupies the last described position, the shafts 46 and 45 remain stationary and no feed movement is transmitted to the rolls 47.

When the handle 86 is in the position shown by full lines in Fig. 1, the trip latch 38 is in the position shown by broken lines 75 in Figs. 2 and 8, at which time the tail-piece 88 is in front of the trip arm 39, as shown in said Fig. 1, and the screw 41 in the end of said latch is out of the path of movement of the head bracket 33, and the trip arm 39 80 in this position is held against the tail-piece 88 by the spring-pressed pin 43. It is therefore impossible to discontinue the feed operation when the parts are in the position just described, because the tail-piece 88 in 85 its then position prevents movement of the trip arm 39 and stop screw 41.

When the handle 86 is moved to the position shown by dotted lines in Fig. 1, against the stop pin 90, the tail-piece 88 has moved 90 away from the front of the trip arm 39, as before described, to a position where it is opposite the notch 91 in the outer end of said trip arm 39, which is then moved by the spring-pressed pin 43 to the position 95 shown by full lines in Figs. 2 and 8, where in the screw 41 is in the path of movement of the head bracket 33, and said handle 86 is effectually held against further movement to its full-line position until the trip 100 latch 38 is released. This is possible at the next movement of the head 33, through the action of the dies, which engages the end of the screw 41 and rocks the trip latch and moves the same out of the path of the tail-piece 88, so that the handle 86 can be again operated, as above described, so as to re-establish the feeding operation. It will be observed, that with this device, instead of the operator attempting to catch a fast moving handle to throw the feed in or out, as is the case with the ratchet and pawl mechanism in common use, it is only necessary for him to grasp a conveniently located stationary handle that is always in the same 110 relative position. The handle 86 can be moved from its full-line position to its dotted line position in Fig. 1, at any time, irrespective and regardless of any other part. The operator, however, is not at liberty to 120 reverse these operations by throwing the handle 86 into a position that will allow a feed of the wire until the correct time, this being determined by the position of the trip latch 38, which in turn is controlled by the 125 position of the dies. When the handle 86 is in the feed position (full lines, Fig. 1), it cannot be moved farther to the right, as the

square end 92 of the link 87 abuts against the end face of the slot in the said handle (see Fig. 3), and the center of the pin 98 is slightly beyond the dead center sufficiently to hold it in position and resist any strain upon the roll arm 85 by the contact of the roll 81 thereon. Normally the handle 86 is in such position as to permit successive feeding movements and is only actuated when it is desired to discontinue the feed for any purpose.

There are minor changes and alterations that can be made within my invention, and I would therefore have it understood, that I do not limit myself to the exact construction herein shown and described, but claim all that falls fairly within the spirit and scope of my invention.

Having described my invention, what I claim as new and desire to secure by Letters Patent, is:

1. In a feed mechanism, the combination with companion rotary shafts; of an operative connection therebetween; means for intermittently rotating said shafts, comprising a notched element; a member covering the notch in said notched element; an independent member within said notch mounted so that in one position it contacts with one face of the notch and one face of said member covering the notch; means for imparting an intermittent rotary movement to said notched element; means, movable in the path of said independent member, and having contact therewith, whereby the frictional engagement of said independent member with said notched element and covering member is broken, the center of said latter means being located at a point more distant from the center of said clutch than that of the independent member; a rock member connected with said latter means; and a movable member mounted in the path of said rock member and controlling the movement thereof.

2. In a feed mechanism, the combination with companion rotary shafts; of an operative connection therebetween; means for intermittently rotating said shafts, comprising a notched element; a member covering the notch in said notched element; an independent member within said notch mounted so that in one position it contacts with one face of the notch and one face of the said member covering the notch; means for imparting an intermittent rotary movement to said notched element; a rock member connected with said independent member and movable therewith; and a member mounted so as to be moved toward and away from said notched element, and engaging said rock member, for holding said independent member in such position that it will move as a unit with said notched element or inde-

pendently and by reason thereof break the contact of said independent member with said notched element and covering member.

3. In a feed mechanism, the combination with companion rotary shafts; of an operative connection therebetween; means for intermittently rotating said shafts, comprising a notched element; a member covering the notch in said notched element; an independent member within said notch mounted so that in one position it contacts with one face of the notch and one face of the said member covering the notch; means for imparting an intermittent rotary movement to said notched element; a trip member in the path of said independent member; means for mounting said trip member so that it may move with or independently of said notched element, said means comprising a curved element connected with a fixed part; an intermediate member between said curved element and said trip member and movable with the trip member; means for moving said curved element toward and away from the axis of said notched element; and means for maintaining said intermediate member in contact with said curved element in its various positions.

4. In a feed mechanism, the combination with companion rotary shafts; of an operative connection therebetween; means for intermittently rotating said shafts, comprising a notched element; a member covering the notch in said notched element; an independent member within said notch mounted so that in one position it contacts with one face of the notch and one face of the said member covering the notch; means for imparting an intermittent rotary movement to said notched element; a trip member in the path of said independent member; means for mounting said trip member so that it may move with or independently of said notched element; and means comprising a rock lever having an operative connection with said trip member, and a roll arm connected with a fixed part and movable toward and away from said notched element and into and out of the path of movement of one end of said rock lever for operating said trip member.

5. In a feed mechanism, the combination with companion rotary shafts; of an operative connection therebetween; means for intermittently rotating said shafts, comprising a notched element; a member covering the notch in said notched element; an independent member within said notch mounted so that in one position it contacts with one face of the notch and one face of the said member covering the notch; means for imparting an intermittent rotary movement to said notched element; a trip member in the path of said independent member;

means for mounting said trip member so that it may move with or independently of said notched element, said means comprising a rock arm, a roll arm having a curved face thereon, means for moving said roll arm so that said curved face may be either concentric or eccentric with the axis of said notched element, and means for holding said rock arm against said curved face when the same is in the concentric position whereby the said independent member will move as a unit with said notched element.

6. In a feed mechanism, the combination with companion rotary shafts; of an operative connection therebetween; means for intermittently rotating said shafts, comprising a notched element; a member covering the notch in said notched element; an independent member within said notch mounted so that in one position it contacts with one face of the notch and one face of the said member covering the notch; means for imparting an intermittent rotary movement to said notched element; a trip member in the path of said independent member; means for mounting said trip member so that it may move with or independently of said notched element, said means comprising a rock arm, a roll arm having a curved face thereon, means, as a handle, pivotally mounted upon a fixed part, for moving said roll arm so that the curved face thereon may be either concentric or eccentric with the axis of said notched element, and a connection between said handle and roll arm; and means for holding said rock arm against said curved face when the same is in its con-

centric position whereby the said independent member will move as a unit with said notched element. 40

7. In a feed mechanism, the combination with companion rotary shafts; of an operative connection therebetween; means for intermittently rotating said shafts, comprising a notched element; a member covering 45 the notch in said notched element; an independent member within said notch mounted so that in one position it contacts with one face of the notch and one face of the said member covering the notch; means for imparting an intermittent rotary movement to said notched element; a trip member in the path of said independent member; and means for mounting said trip member so that it may move with or independently of 50 said notched element, comprising a rock arm, a roll arm, having a curved face thereon, means for moving said roll arm so that said curved face may be either concentric or eccentric with the axis of said notched element, a handle pivotally mounted upon a fixed part, a connection between said handle and roll arm that is either on or slightly beyond a dead center when the curved face on said roll arm is substantially concentric 55 with the axis of said notched element, and means for holding said rock arm against said curved face when the same is in its concentric position, whereby the said independent member will move as a unit with said notched 60 element. 65

In testimony whereof I have hereunto affixed my signature.

RICHARD LESTER WILCOX.
